UNITED STATES PATENT OFFICE.

LEWIS J. FISHER, OF REEDSBURG, WISCONSIN.

STEAM HEATING SYSTEM.

Application filed July 27, 1925. Serial No. 46,479.

This invention relates to improvements in steam heating apparatus and has as its general object to provide an improved steam heating apparatus in which provision is made for the delivery of the water of condensation from the circulating system to a receiving chamber, from which it is automatically returned to the boiler, and the invention contemplates the provision of means whereby the delivery or return of water of condensation to the boiler will be effected with certainty and without any waste of steam or any appreciable reduction in the steam pressure in the circulating system.

Another object of the invention is to provide, in connection with the chamber for receiving the water of condensation, a novel construction of valve operating through the medium of a float in said chamber to automatically admit steam into the chamber above the water of condensation accumulated therein, when a predetermined volume of water has accumulated in the chamber, so that steam from the boiler is utilized for effecting return of the water of condensation to the boiler, only after a sufficient quantity of water of condensation has accumulated to warrant such return.

Another object of the invention is to provide, in a steam heating system of the class referred to, means whereby the employment of air vent valves at each radiator may be avoided and a single valve employed as a substitute therefor, and in this connection the invention also contemplates the provision of a novel form of water leg for collecting the water of condensation and delivering the same to the receiving chamber.

In the accompanying drawings:

Figure 1 is a schematic perspective view illustrating a steam heating system embodying the invention.

Figure 2 is a detail vertical longitudinal sectional view through that portion of the apparatus embodying the invention, parts being shown in elevation.

Figure 3 is a vertical transverse sectional view taken substantially on the line 3—3 of Figure 2, looking in the direction indicated by the arrows.

Figure 4 is a vertical transverse sectional view through the controlling valve of the invention, illustrating the valve in closed position.

Figure 5 is a vertical longitudinal sectional view through the valve, taken substantially on the line 5—5 of Figure 4, looking in the direction indicated by the arrows.

Figure 1 of the drawings illustrates schematically a steam heating system in which the principles of the invention are embodied, and in this figure the numeral 1 indicates several radiators constituting part of the system and which are provided with the usual manually operable cut-off valves 2, through the adjustment of which the supply of steam to the radiators may be controlled. The numeral 3 indicates a steam boiler of the ordinary type and the numeral 4 indicates the steam supply pipe which leads from the boiler and has the usual branch pipes connected to it and to the several radiators 1, by way of the valves 2. In the ordinary system, as is well known, each radiator is provided with an air vent valve located upon and in communication with that section of the radiator more remote from the section with which the cut-off valve 2 is connected, but in the system embodying the invention, as in other systems of this general class, pipes 5 are connected to the end sections of the radiators and are placed in communication with a return pipe indicated by the numeral 6. This pipe 6, in the present invention, is connected to one branch 7 of a water leg which is indicated by the numeral 8, the other branch of the water leg being indicated by the numeral 9, and the two branches being connected at their lower ends by a short connecting pipe 10 and the usual pipe fittings required to establish such a connection and position the branches 7 and 9 parallel to each other. The delivery end of the return pipe 6 and the upper end of the branch 7 of the water leg are placed in communication with each other through the medium of a T-coupling 11, and a pipe 12 is fitted to the upper branch of the coupling and supports at its upper end, a vent valve 13 which may be of any of the ordinary constructions and which provides for escape of air from the system and constitutes a substitute for the individual vent valves ordinarily provided one upon each of the radiators of the system. At this point, it will be evident that condensed steam, and air displaced from the radiators, which would ordinarily issue from the individual air vent valves, is conducted by the pipe 6 and

105
110

its branches to the water leg 8. A pipe 14 leads at right angles from the upper end of the branch 9 of the water leg 8 substantially at a point opposite the connection of the pipe 6 with the branch 7 of said leg and communicates with the upper portion of a receiving or accumulating chamber for the water of condensation, indicated in general by the numeral 15, a check valve 16 being interposed in the said branch 14 so that when steam pressure is admitted to the chamber 15 under conditions to be presently explained, the steam will be prevented from entering the water leg 8, although, on the other hand, the water of condensation which has accumulated in the water leg 8 may readily flow therefrom through the pipe 14 and past the check valve 16 into the said accumulating chamber.

The accumulating chamber 15 comprises a hollow cylindrical body 16 having a closed bottom 17 and provided at its side opposite the side through which the pipe 14 opens, with a lateral extension 18 including a substantially semi-cylindrical bottom wall 19 and side walls 20, the extension of the body being provided with a partition wall 21 located between the open side of the extension which communicates with the accumulating chamber 16 proper and an outer end wall which is indicated by the numeral 22. The walls of the accumulating chamber proper and its extension are provided with a continuous outstanding flange 23, and a cover plate 24 constituting a closure for the chamber and its extension is disposed upon the top of the chamber and its extension with its margin resting upon a packing gasket 25 which is interposed therebetween and the flange 23, suitable fastening devices being provided for securing the cover plate in position, such for example as stud bolts 26 fitted through the cover plate and threaded into the upper edge of the partition wall 21, a packing 27 being interposed between the under side of the cover plate and said upper edge of the partition wall and constituting a part of the packing gasket 25. A vent valve 28 of the thermo-type is carried by the cover plate 24 and is located axially above the accumulating chamber 16 and provides for the escape of air therefrom.

A pipe 29 is placed in communication with the steam chamber 30 which is defined by the side walls 20 of the extension of the accumulating chamber and the partition wall 21 and end wall 22, and leads to and communicates with the pipe 4, or it may be independently placed in communication with the steam chamber of the boiler 3. In any event, this pipe is to supply steam under pressure to the said chamber 30 under conditions which will presently be set forth. A pipe 31 leads from the bottom 17 of the accumulating chamber to the water chamber

of the steam boiler, and a check valve 32 is interposed in this pipe to prevent any back flow of water from the boiler into the accumulating chamber.

The invention contemplates delivery of steam under pressure from the steam chamber 30 into the accumulating chamber after a predetermined volume of water of condensation has accumulated in said accumulating chamber, so as to effect delivery of the water from the accumulating chamber through the pipe 31 back into the boiler, and in order that this operation may be effected automatically, there is provided a control valve 33 and means for automatically actuating the same. The control valve comprises a cylindrical hollow casing 34 having a head 35 removably secured to one end thereof and closing the said end, the other end of the casing having an integral closure head 36 indicated by the numeral 36. The head 36 of the casing is formed with an axially located bore 37, and one end of a tubular conduit 38 is fitted into the bore and secured by a set screw 39 which is threaded through the said head 36, the said head being preferably substantially of the conical form shown in the drawings. An opening 40 is formed in the partition wall 21 and a bushing 41 is fitted into the said opening and provided with a circumscribing shoulder 42 which bears against that side of the partition wall which is presented to the interior of the steam chamber 30. The bushing 41 is provided with a bore 43, and the tubular steam conduit 38 extends through the bore and is threaded at its end to accommodate a nut 44 which is tightened to bear against the end of a stuffing box 45 which is threaded onto the corresponding end of the bushing 41, the packing 46 within the stuffing box snugly surrounding the end of the conduit 38 as shown in Figure 2. A packing washer 47 of rubber or other suitable packing material is fitted upon the tubular conduit 38 and a metal washer 48 is similarly fitted upon the conduit, and the minor end of the head 36 of the valve casing bears against the washer 48 and binds the packing washer 47 against that side of the partition wall 21 which is presented to the interior of the extension 18 of the accumulating chamber, the parts being held in this relationship through the tightening of the nut 44. It will be evident at this point that the valve casing 33 may be rotated with the conduit 38, and, if desired, anti-friction bearing balls 49 may be arranged within a ball race in the bushing 41 and in a series surrounding the conduit 38 so as to provide for sufficient freedom of rotative movement of the valve casing 34 to prevent sticking thereof. The valve casing 34 is provided in its under side with an outlet port 50 preferably formed in the bottom of an arcuate guideway 51

formed in the under side of the said casing 34, and a ball valve 52 is arranged within the casing and adapted to have movement in the guideway 51, the valve being likewise 5 adapted to rest upon a valve seat 53 which surrounds the port 50. Normally, the ball valve 52 will rest upon the seat 53 and thus prevent the escape of steam from the valve 10 casing into the accumulating chamber by way of the port 50, but the invention contemplates the provision of means for automatically displacing the ball valve when the water of condensation in the accumulating chamber 16 has reached a predetermined 15 level, and this means will now be described.

A boss 54 is formed or provided upon the under side of the valve casing 34 exterior thereto, and an arm 55 is mounted upon the boss at one side thereof and extends beyond 20 the head 35 of the valve casing and into the upper portion of the accumulating chamber 16. A flat circular float 56 is arranged within the accumulating chamber, and a yoke 57 is associated with the float and comprises spaced parallel arms 58 each comprising 25 a section 59 secured at its lower end to the float body 56, and an upper section 60 which is preferably formed with a series of openings 61 threaded to accommodate a screw 62 which is fitted through an opening 30 in the corresponding lower sections 59, so that the arms of the yoke are adjustable as to length. The upper ends of the sections 60 of the arms of the yoke are connected by a cross bar 63, and a second cross bar 64 extends between said sections 60 below and in 35 spaced relation to the cross bar 63. It will be observed by reference to Figures 2 and 3 of the drawings, that the arm 55 at its outer end extends between the sections 60 of the arms of the yoke and between the cross bars 63 and 64, and it will furthermore be 40 evident that when the float 56 is in the lowered position shown in Figure 2 of the drawings, the cross bar 63 will engage the arm 45 and the valve casing will assume the position shown in Figures 4 and 5 of the drawings, in which position the ball valve 52 will rest upon its seat 53, thus preventing the 50 entrance of steam under pressure into the accumulating chamber. In this position of the parts, the float body 56 will rest upon the bottom 17 of the accumulating chamber 16.

55 In the operation of the system, the air displaced from the radiators at the time the furnace is fired and steam is initially generated, will be delivered through the pipe 5 to the pipe 6 and will escape by way of the vent valve 13, and after the steam pressure has been built up to the point where the radiators are completely supplied with steam, the surplus steam, and such water of condensation as has accumulated, will be 60 delivered through the said pipe 5 to the

main conducting pipe 6 and the steam will, of course, condense by the time it reaches the water leg 8, the water of condensation accumulating in said leg until it overflows, past the check valve and through the pipe 70 14, into the accumulating chamber 16. As the water level rises in the accumulating chamber, the float body 56 will, of course, rise, carrying with it the yoke 57. When the float has reached a level such that the 75 cross bar 64 engages the end of the arm 55, the valve casing 33 will, of course, be rotated through the upward thrust exerted by the cross bar 64 against the arm. In order that, when the valve casing 34 is rotated, the 80 ball valve 52 may be automatically displaced from its seat 53, a displacing element, indicated by the numeral 65, is pivotally mounted as at 66, in a recess 67 in the under side of the boss 54 and this element preferably 85 comprises a flat-sided approximately triangular body 68 provided at its corner which is next adjacent the port 50, with a displacing finger 69 curved in the general direction of the said port. The opposite 90 edge of the body 68 of the displacing element rests in engagement with the rounded surface 70 of an abutment 71 secured in any suitable manner upon the inner side of the adjacent side wall 18 of the accumulating 95 chamber extension; and it will be evident that as the casing 34 is rotated, the said edge of the displacing element will ride against the rounded surface of the abutment 71 and the element will be swung about its pivot to 100 project its displacing finger 69 through the port 50 to engage and displace the ball valve 52. At this time, steam under pressure will be admitted from the steam chamber 30, through the conduit 38, and the port 50, into 105 the accumulating chamber 16 with the result that the water of condensation which has accumulated in the said chamber will be displaced and caused to flow through the pipe 31 past the check valve 32 into the 110 boiler 3, there to be converted into steam. Of course, as the water of condensation is displaced from the said chamber 16, the float body 56 will lower until it rests upon the bottom 17 of the said chamber, at which 115 time all of the water of condensation will have been expelled from the chamber. As the float body approaches the bottom of the accumulating chamber, the upper cross member 63 of the yoke 57 will pull downwardly upon the arm 55, thus effecting rotation of the valve casing 34 until it assumes the position shown in Figures 4 and 5 of the drawings. As the valve casing is rotated to its normal position, the ejector or displacing element 65 will, by gravity, remain in engagement with the abutment 71, and the port 50 will, of course, recede from the finger 69 of the displacing element so that the 120 ball valve 52 is permitted to roll in the 125 130

guideway 51 to position resting upon its seat 53, thereby cutting off the supply of steam under pressure to the accumulating chamber until such time as a sufficient 5 volume of water of condensation has again accumulated within the chamber to elevate the float 56 to such height as to again effect rotation of the valve casing, whereupon the above described operation will be repeated: 10 It will be evident from the foregoing description of the invention that the system is entirely automatic in its operation and requires no attention whatsoever on the part of the one whose duty it is to attend to the 15 firing of the furnace.

Having thus described the invention, what I claim is:

1. In steam heating apparatus, means for automatically returning the water of condensation from the radiator to the boiler, comprising an accumulating chamber, means for admitting water of condensation to the chamber, a float within the chamber, means for supplying steam to the chamber, means 20 for controlling the supply of steam, the said means comprising a rotatable valve casing having an inlet for the steam and an outlet port communicating with the chamber and provided with a valve seat, a ball valve resting upon the seat to close the outlet and displaceable in the rotative movement of the said valve chamber, means actuated through rise and fall of the float for effecting rotation of the valve casing, and means for conducting water of condensation from the chamber. 25
2. In steam heating apparatus, means for automatically returning the water of condensation from the radiator to the boiler, comprising an accumulating chamber, means 30 for admitting water of condensation to the chamber, a float within the chamber, means for supplying steam to the chamber, means for controlling the supply of steam, the said means comprising a rotatable valve chamber having an inlet for the steam and an outlet 35 communicating with the chamber and provided with a valve seat, a ball valve resting upon the seat and closing the said outlet, and displacing means actuated through rise of the float and rotation of the valve chamber, to displace the said valve and provide for the admission of steam to the chamber upon accumulation of a volume of water 40 of condensation in the chamber, and means for conducting the water of condensation from the chamber. 45

3. In steam heating apparatus, means for automatically returning the water of condensation from the radiator to the boiler, comprising an accumulating chamber, means 50 for admitting water of condensation to the chamber, means for conducting the water of condensation from the chamber, a float within the chamber, means for supplying steam to the chamber, and means for controlling the supply of steam to the chamber, said means comprising a rotatable valve casing having an inlet for the steam and also having an outlet provided with a valve seat, a ball valve to rest upon the seat and close the 55 outlet in one position of rotative adjustment of the said casing, a displacing element pivotally supported by the valve casing and having a part engageable through the said outlet to displace the valve, an abutment in the path of movement of the displacing element in the rotation of the valve casing to another position of adjustment, and means actuated through rise and fall of the float 60 for rotating the valve casing. 65

4. In steam heating apparatus, means for automatically returning the water of condensation from the radiator to the boiler, comprising an accumulating chamber, means 70 for admitting water of condensation to the chamber, means for conducting the water of condensation from the chamber, a float within the chamber, means for supplying steam to the chamber, and means for controlling the supply of steam to the chamber, said means comprising a rotatable valve casing having an inlet for the steam and also having an outlet provided with a valve seat, a ball valve to rest upon the seat and close the 75 outlet in one position of rotative adjustment of the said casing, a displacing element pivotally supported by the valve casing and having a part engageable through the said outlet to displace the valve, an abutment in the path of movement of the displacing element in the rotation of the valve casing to another position of adjustment, and means actuated through rise and fall of the float 80 for rotating the valve casing. 85

5. In steam heating apparatus, means for automatically returning the water of condensation from the radiator to the boiler, comprising an accumulating chamber, means 90 for admitting water of condensation to the chamber, means for conducting the water of condensation from the chamber, a float within the chamber, means for supplying steam to the chamber, and means for controlling the supply of steam to the chamber, said means comprising a rotatable valve casing having an inlet for the steam and also having an outlet provided with a valve seat, a ball valve to rest upon the seat and close the 95 outlet in one position of rotative adjustment of the said casing, a displacing element pivotally supported by the valve casing and having a part engageable through the said outlet to displace the valve, an abutment in the path of movement of the displacing element in the rotation of the valve casing to another position of adjustment, and means actuated through rise and fall of the float 100 for actuating the valve, the last mentioned means comprising an arm extending from the valve casing, and a member carried by the yoke and having spaced abutments for coaction with the said arm in the elevated and lowered positions of the float. 105

In testimony whereof I affix my signature.

LEWIS J. FISHER. [L. S.]
